UNITED STATES PATENT OFFICE.

GEORGE W. O'BRYAN, OF CAMBRIA, VIRGINIA.

COMBINATION WINDOW-SCREEN AND FLY-TRAP.

1,092,505.

Specification of Letters Patent.

Patented Apr. 7, 1914.

Application filed January 30, 1913. Serial No. 745,269.

To all whom it may concern:

Be it known that I, GEORGE W. O'BRYAN, a citizen of the United States, residing at Cambria, in the county of Montgomery and State of Virginia, have invented a new and useful Combination Window-Screen and Fly-Trap, of which the following is a specification.

The invention forming the subject matter of the present application relates to a combination window screen and fly trap, the primary object of the present invention being to provide a novel and improved window screen and in combination therewith a novel trap for catching flies and other insects.

A further aim of the present invention is to provide a window screen having a compartment or chamber therein provided with inlets for the insects along the bottom of the screen and on either side thereof, novel means being provided for preventing the escape or retreat of the insects, and for opening the compartment.

This invention also comprehends the provision of a device of the character indicated which shall be comparatively simple and inexpensive in construction, as well as convenient, durable and efficient in its use.

To the above and other ends, the present invention resides in the provision of the novel construction, arrangement and combination of parts hereinafter set forth in detail and pointed out in the appended claims, it being understood that this device is susceptible of alterations and deviations in its details within the scope of what is claimed without departing from the spirit of the invention.

The invention has been illustrated in its preferred embodiment in the accompanying drawings, wherein similar reference characters have been employed to denote corresponding parts, and wherein:

Figure 1 is an elevation of a window screen and trap constructed in accordance with the present invention, parts being broken away. Figs. 2, 3 and 4 are sectional views taken on the lines 2-2, 3-3 and 4-4 of Fig. 1, respectively. Fig. 5 is a fragmental perspective view of a detail. Fig. 6 is an elevation, similar to Fig. 1, of another form of the invention. Figs. 7 and 8 are sectional views taken on the lines 7-7 and 8-8 of Fig. 6, respectively. Fig. 9 is an elevation of another variation, parts be-

ing broken away. Fig. 10 is a section on line 10-10 of Fig. 9. Fig. 11 is a sectional view of a further modification. Fig. 12 is a sectional detail of a means for adjustably connecting an extension to the main frame. Fig. 13 is a detail, partly in section, disclosing a means for opening the door.

Referring in detail to the drawings, and particularly to Figs. 1 to 5, inclusive, there has been designated by the numeral 10 a window screen frame, similar to the ordinary window screen frame, but altered in its details to accommodate the present invention, the details being apparent to those skilled in the art. A meshed wire or reticulated panel 11 is secured to one face of the frame 10, the lower edge of the panel 11 extending over the lower rail of the frame and being spaced therefrom by a series of blocks 12. The blocks 12 in spacing the panel 11 from the lower rail of the frame 10 provide a series of vertical inlets or channels 13 along the corresponding face of the said rail. A door frame 14 is hinged to the upper rail of the frame 10 on the other face of the said frame, the door frame having a meshed wire or reticulated panel 15 secured thereto. The lower edge of the panel 15 passes over the corresponding face of the bottom rail of the frame 10 and is spaced therefrom by blocks 12 secured to the said rail in order to provide a series of inlets 13 along the corresponding face of the rail. A pair of meshed wire or reticulated cones 16 are secured to the panel 15, the bases and apices of the cones 16 being open. The base of the cones 16 completely fill the space between the lower ends of the panels 11 and 15, and the cones 16 are constructed of fine wire mesh, a number of the wires projecting over the opening in the apices of the cones, as designated by the numeral 17. A latch 18 is pivoted to each stile of the frame 10 and is adapted to engage the corresponding stile of the door frame 14 when the door is swung closed. An elongated pan or bait holder 19 is seated on the lower rail of the frame 10 below the cones 16, while a second pan or bait holder 20 is secured to the panel 11 adjacent the upper rail of the frame 10. Should the frame 10 be narrower than the window casing to which the screen is to be applied, an extension frame 21 may be secured to each stile of the frame 10 in order to accommodate the particular window casing, the said frame 21 having reticulated

panels 22. The panels 11 and 15 provide a confining chamber or compartment 23 therebetween for the insects, as will hereinafter appear.

5 In use, the screen is applied to the window casing as is customary, and the flies or other insects are lured to the vicinity of the lower rail of the frame 10 by any suitable bait contained in the holder 19, the insects then passing upward through the inlets 13 and partaking of the bait held in the holder 19. The insects will then ascend into the cones 16 and will find their way to the apices of the cones. The insects will then 10 pass through the openings at the apices of the cones, the wire 17 being flexed readily as the insects pass through the openings, but normally preventing the retreat or escape of the insects from the chamber 23 into the cones. The insects are thus captured in the chamber 23, the bait held within the holder 20 assisting in luring the insects into the said chamber, and the bait held in the holder 20 may be of such a character as to kill the 15 insects, in which event, they will drop to the bottom of the chamber 23. The dead insects accumulating in the bottom of the chamber 23 may be removed from time to time, by swinging the door open, this being 20 permitted by releasing the latches 18 from the door. When the door is open, the insects will drop out, the cones 16 swinging with the door and thus permitting the bait in the two holders to be replenished whenever it is desired. When the door is closed, the cones 25 16 will be swung over the holder 19 as before, and the trap will again be ready for operation. It will be noted, that the cones 16 are adapted to receive the insects advancing inwardly through the inlets along both faces of the lower rail of the frame 10, the inlets 13 being of such size, that the insects will rise into the cones 16 in preference to retreating through the said inlets.

30 45 In the form shown in Figs. 6, 7 and 8, the window screen frame has been designated by the numeral 10', the upper or inner edge of the lower rail being inclined as designated by the numeral 10^c. Tapered pieces 10^b are secured to one face of the stile of the frame 10' and a supplemental rail 10^c is secured to the respective side of the lower rail of the frame 10'. A meshed wire or reticulated panel 11' is secured to the corresponding face of the frame 10' and over the pieces 10^b, the lower edge of the panel 10' being spaced from the supplemental rail 10^c. The lower edge of the panel 11' is spaced from the rail 10^c by means of blocks 12' secured to the rail 10^c, thus providing a series of inlets 13' along the outer face of the rail 10^c. A meshed wire or reticulated arch 11^a extending throughout the width of the frame 10' has one limb attached to the 35 bottom of the panel 11' and its other limb

secured between the supplemental rail 10^c and the lower rail of the frame 10', it being preferable to construct the panel 11' and the arch 11^a from the same piece of material. The meshed wire or reticulated panel 11' is secured to the other face of the frame 10' and extends from the upper rail of the said frame to a point midway between the rails of the frame. A door frame 14' is hinged to the frame 10' along the bottom of the reticulated panel 11'', the door frame including the tapered side pieces 14^b and the lower rail 14^c secured between the lower ends of the said pieces and adapted to normally seat against the lower rail of the frame 10'. A meshed wire or reticulated panel 15' is secured to the outer face of the door frame 14' and is spaced from the rail 14^c by means of blocks 12' secured to the outer face of the rail 14^c, which blocks provide a series of inlets 13' along the outer face of the said rail. A meshed wire or reticulated arch 15^a extending throughout the width of the frame 10' has one limb thereof attached to the bottom of the panel 15' and has the other limb secured to the inner face of the rail 14^c, it is preferable to have the panel 15' and the arch 15^a constructed of the same piece of material. The arch 11^a is provided with a series of openings along its ridge, at the points indicated at 11^b, while the arch 15^a is provided with a similar series of openings along its ridge at the points indicated at 15^b, and the openings of the respective arches are arranged in staggered relation to one another. Suitable cones 16' are secured at their bases to the ridges of the arches over the openings therein, the bases and apices of the cones being open and the cones being constructed of fine wire mesh in order to provide the wires 17' normally closing the openings of the apices of the cones, but permitting the passage of the insects through the said openings. The cones 16' are also attached to the corresponding panels 11' and 15' in order to eliminate any space between the cones and the said panels. A screw or locking bolt 18' is carried by the lower rail of the door in order to engage the lower rail of the frame 10' when the door is closed, the details of which are of no moment. It is understood that the locking means may be of any form, such as is most desirable. Bait holders or pans 19' are seated on the rails 10^c and 14^c within the corresponding arches and are designed to contain suitable bait for luring the insects into the vicinity of the inlets 13'. The confining chamber 23' between the panels 11' and 15' extends downwardly between the arches 11^a and 15^a to the lower rail of the frame 10', as will be clearly apparent by reference to Fig. 7. In use, the insects pass upwardly through the inlets 13', being lured by the bait contained in the holders 19', and thereby pass-

130

ing into the primary confinement chambers provided by the arches. The insects then pass upwardly through the openings along the ridges of the arches into the cones 16' 5 thence passing through the openings of the apices of the cones into the confinement chamber 23'. The insects may be destroyed within the chamber 23' by means of suitable bait contained within the chamber or in any 10 other suitable manner, the dead insects dropping between the arches onto the inclined edge 20 of the lower rail of the frame 10'. Thus, when the door is swung open, the insects will be discharged, and when the door 15 is closed, the trap is again ready for operation.

In the variation illustrated in Fig. 9, an inverted V-shaped member 30 is secured to the door frame and panel thereof and is adapted 20 to swing against a V-shaped member or strip 32 secured to the window screen frame and panel to thus provide a primary or confining chamber. The member 30 is provided with an opening 33 at its apex over which opening 25 is secured a cone 34.

As depicted in Fig. 11, the door 35 is only coextensive with the lower half of the window screen and the window screen frame is only provided with a single panel above the 30 door. The reticulated member 36 secured to the panel of the door 35 provides the primary confining chamber, and when the door is closed, the reticulated member 36 is spaced from the reticulated member 37 secured to the panel of the window screen. 35

In Fig. 12, a bar 38 is secured to the stile 39 of the window screen frame, and interlocks with the rails 40 of the extension in order that the extension may be slid or 40 adjusted to accommodate the device to various widths of windows or doors.

In Fig. 13, there is illustrated an actuating arm 41 pivoted to the door 42 and passing through the window screen frame, so that 45 when the door is disposed on the outside, the same may be opened from the inside, as will be apparent.

Having thus described the invention what is claimed as new is:—

50 1. In an insect trap of the class specified, a window screen frame, a reticulated panel secured to one face thereof and spaced from the lower rail of the frame to provide an inlet, a door frame hinged to the other face of the said frame and having a reticulated panel, and a reticulated member between the lower rail and the panel of the window screen frame forming a chamber to receive the insects from the said inlet, said reticulated member having openings to admit the insects into the chamber between the said panels.

55 2. In an insect trap of the class specified a window screen frame, a reticulated panel secured to one face thereof and spaced from

the lower rail of the frame to provide an inlet, a door frame hinged to the other face of the frame and having a reticulated panel, and a reticulated arch between the lower rail and the panel of the window screen 70 frame to receive the insects from the said inlet, the said arch having openings along the ridge thereof to admit the insects into the chamber between the said panels.

3. In an insect trap of the class specified, 75 a window screen frame including a lower rail, a reticulated panel secured to one face thereof, a door frame hinged to the other face of the said frame and including a lower rail to seat against the lower rail of the said frame, a reticulated panel secured to the door frame and spaced from the lower rail of the door frame to provide an inlet, and a reticulated member between the rail and panel of the door frame and forming a 80 chamber to receive the insects from the said inlet, the said reticulated member having openings to admit the insects into the chamber between the said panels.

4. In an insect trap of the class specified, 85 a window screen frame including a lower rail, a reticulated panel secured to one face thereof and spaced from the lower rail of the frame to provide an inlet, a door frame hinged to the other face of the said frame 90 and including a lower rail to seat against the lower rail of the said frame, a reticulated panel secured to the door frame and spaced from the lower rail of the door frame to provide an inlet, and reticulated members between the lower rails and the corresponding 95 panels to provide chambers to receive the insects from the respective inlets, the said reticulated members having openings to admit the insects into the chamber between the 100 said panels.

5. In an insect trap of the class specified, 105 a window screen frame including a lower rail, a reticulated panel secured to one face thereof and spaced from the lower rail of the frame to provide an inlet, a door frame hinged to the other face of the said frame and including a lower rail to seat against the lower rail of the said frame, a reticulated panel secured to the door frame and spaced 110 from the lower rail of the door frame to provide an inlet, and reticulated arches between the lower rails and the corresponding panels to receive the insects from the respective inlets, the arches having openings 115 along the ridges thereof, to admit the insects 120 into the chamber between the said panels.

6. In an insect trap of the class specified, 125 a window screen frame including a lower rail, a reticulated panel secured to one face thereof and spaced from the lower rail of the frame to provide an inlet, a door frame hinged to the other face of the said frame and including a lower rail to seat against the lower rail of the said frame, a reticulated 130

panel secured to the door frame and spaced from the lower rail of the door frame to provide an inlet, reticulated arches between the lower rails and the corresponding panels to receive the insects from the respective inlets, the said arches having openings along the ridges thereof, and cones secured on the ridges of the arches over the openings, the bases and apices of the cones being open.

10 7. In a device of the class specified, a window screen frame including a lower rail, a supplemental rail secured to one face of the lower rail of the said frame, a reticulated panel secured to the corresponding face of the said frame and spaced from the supplemental rail to provide an inlet, a reticulated arch having one limb attached to the lower edge of the said panel and the other limb secured between the said rails, a door frame

hinged to the other face of the aforesaid frame and including a lower rail to swing against the other face of the lower rail of the aforesaid frame, a reticulated panel secured to the door frame and spaced from the lower rail thereof to provide an inlet, and a reticulated arch having one limb attached to the lower edge of the last mentioned panel and the other limb secured to the inner face of the lower rail of the door frame, the arches having openings along the ridges thereof.

In testimony that I claim the foregoing as my own, I have hereto affixed my signature in the presence of two witnesses.

G. W. O'BRYAN.
